UNITED STATES PATENT OFFICE

149,698

DESIGN FOR A SHOE SOLE

Alfred E. Shaffer, Mishawaka, and Leo D. Morningstar, South Bend, Ind., assignors to Mishawaka Rubber and Woolen Manufacturing Company, Mishawaka, Ind., a corporation of Indiana

Application January 29, 1948, Serial No. 144,138

Term of patent 14 years

(Cl. D7—5)

To all whom it may concern:

Be it known that we, Alfred E. Shaffer and Leo D. Morningstar, both citizens of the United States, residing at Mishawaka and South Bend, respectively, in the county of St. Joseph and State of Indiana, have invented a new, original, and ornamental Design for a Shoe Sole, of which the following is a specification, reference being had to the accompanying drawing, forming part thereof.

Fig. 1 is a bottom plan view of a shoe sole showing our new design;

Fig. 2 is a longitudinal sectional view on the line 2—2 of Fig. 1; and

Fig. 3 is a cross sectional view on the line 3—3 of Fig. 1.

We claim:

The ornamental design for a shoe sole, as shown and described.

ALFRED E. SHAFFER.
LEO D. MORNINGSTAR.
